UNITED STATES PATENT OFFICE.

RALPH F. KNIGHT, OF BEVERLY, MASSACHUSETTS, ASSIGNOR TO UNITED SHOE MACHINERY CORPORATION, OF PATERSON, NEW JERSEY, A CORPORATION OF NEW JERSEY.

MOLD FOR MANUFACTURING OF RUBBER SOLES.

Application filed March 1, 1920. Serial No. 362,275.

To all whom it may concern:

Be it known that I, RALPH F. KNIGHT, a citizen of the United States, residing at Beverly, in the county of Essex and State 5 of Massachusetts, have invented certain Improvements in Molds for Manufacturing of Rubber Soles, of which the following description, in connection with the accompanying drawings, is a specification, like 10 reference characters on the drawings indicating like parts in the several figures.

This invention relates to the manufacture of soles of rubber or rubber compound, which for convenience will hereinafter be 15 referred to as rubber soles, and is herein illustrated as embodied in a mold for making a turn sole.

In the manufacture of rubber-soled turn shoes it is common in some factories to employ a sole having integral with it a rubber heel. A rubber sole whether or not it is provided with an integral rubber heel, has on its upper side a sewing shoulder or sewing-rib which, in case shoes having sewed-seats 20 are to be made, extends entirely around the sole at a distance from the margin, the horizontal margin of the upper face of the sole outside the rib constituting the feather. In the manufacture of the shoe the sole 25 together with an assembled upper is placed wrong side out upon a last, and the upper attached to the sole by stitches which should pass through the base of the rib from outside to inside. In the case of a sole which

30 has no heel, the last is curved slightly downwardly and outwardly along its entire margin; and, in the pulling-over and lasting operation, the entire margin of the sole is caused to conform to this curve, with the 35 result that the feather, which is normally perpendicular to the adjacent wall of the sewing rib or sewing shoulder is, in the lasted shoe, bent downwardly and outwardly so as to give to the needle of the sewing machine free access to the base of the rib or shoulder. In case, however, that the sole 40 carries a heel, the last is recessed to receive the heel; and because of the thickness of the heel and the shape of the recess, the feather 45 in the heel portion of the sole is not bent downwardly with the result that the needle of the sewing machine tends to pass through the rib or shoulder on the heel portion of the sole at points located above the base of

said rib or shoulder thereby producing, 55 when the shoe is turned right side out, a loose heel-seat as well as one which is not as strong as it should be. To avoid this difficulty it has been proposed to provide a sole 60 having an integral heel with a downwardly and outwardly inclined feather around its heel portion, such a sole being disclosed and claimed in co-pending application Serial No. 362,055 filed in the name of George Ferguson and owned by the same assignee 65 as is the present application.

The general object of the present invention is to provide a suitable mold by which the sole of the application and those presenting similar difficulties in their manufacture may readily be made.

Referring now to the accompanying drawings,—

Figure 1 is a perspective of parts of the shank and heel portions of a mold in which 75 the present invention is embodied;

Fig. 2 is a cross-section through the heel portion of the mold;

Fig. 3 is a cross-section through the forepart of the mold;

Fig. 4 is a cross-section through the heel portion of a lasted shoe having a sole made by the mold, the sole being shown in process of being attached to an upper, both sole and upper being wrong side out, and

Fig. 5 is a cross-section similar to Fig. 4 but taken through the forepart of the same shoe.

Referring first to Fig. 5, it will be seen that in the forepart of the lasted shoe the 90 margin of the sole 7 is bent downwardly by reason of having been pulled down upon the curved margin of the bottom of the forepart of the last 9. The feather 11 of the sole is thus inclined downwardly from 95 the base of the sewing-shoulder 13 or sewing-rib 15 to facilitate passage of the needle 17 through said base. In the heel portion of the last the bottom 19 is flat, but even if the bottom of the heel portion of 100 the last had a margin curved like that of the forepart, it would be impractical if not impossible to bend the margin of the thick heel 21 of the sole so as to incline 105 the feather. It has therefore been proposed to form the feather around the heel portion with a permanent inclination as shown in Fig. 4 in order to facilitate the sewing

operation and thereby obtain a more secure heel-seat.

The mold illustrated in Figs. 1 to 3 is designed to produce the sole shown in Figs. 4 and 5. Referring now more particularly to Fig. 3, the upper section 23 is provided with a rib-forming groove 25 which extends entirely around the section, said groove being spaced inwardly from the upright sole-edge-forming wall 27 of the lower member 29; and between the outer wall of the groove and the wall 27 is a wall or surface 31 which determines the shape of the feather 11 of the sole. The surface 31 is corrugated in the forepart of the mold as shown in Fig. 1 for a purpose which need not here be described since it forms no part of the present invention. Surrounded by the groove 25 is a cavity the bottom 33 of which is on a level with the bottom of the groove 25, the purpose of this cavity being to provide in the sole a raised portion to serve as a filler. The lower section 29 has in it a cavity rectangular in cross-section bounded by the sole-edge-forming wall 27 and the tread-surface-forming wall or bottom 35. As thus far described, the mold is in general like those shown in applications Serial No. 188,174 and Serial No. 318,728, Patent 1,354,734 filed in the name of Ferguson and owned by the same assignee as is the present application; and, if the rear part of the section 23 were like the forepart, there would be produced around the margin of the upper face of the sole a horizontal feather extending substantially perpendicularly to the adjacent upright wall or shoulder of the sewing rib. It is desired, however, to produce around the heel end of the sole a feather inclined as shown in Fig. 4. In order to accomplish this and at the same time to maintain the contacting surfaces of the sections in the common plane 37 and the plane without obstructions, the cavity in the upper section 23 is deepened as it approaches the heel end of the section, the feather-forming surface 31 being beveled as shown in Figs. 1 and 2. It should be understood that the cavity in the section 29 grows correspondingly less deep than it would ordinarily have been as it approaches the heel end of the section. In Fig. 2, the dot-and-dash line indicates approximately what would have been the depth of the cavity in the heel end of the section 29 if the depth of the cavity in the member 23 had been kept constant as in the usual mold for producing a horizontal feather all around the sole.

In other words, the sole does not lie flat in the mold as has been the case hitherto but is bent or curved slightly. With the sections of the mold in the positions shown in the figures, the heel portion of the sole would be bent upwardly in the vicinity of

the heel breast line as best shown in Fig. 1. The bend or curvature of the sole produced by the mold is comparatively small; and with a yieldable material such as rubber is of no disadvantage whatever. Indeed, it is doubtful whether, when the molding and vulcanizing operation is carried out in the usual manner, the curvature is permanent. A sole taken from the mold, as it usually is, while still very hot and laid on a flat plate has usually lost all of its curvature so far as a casual inspection will determine, by the time it has cooled. But in any event the curvature, even if it is permanent, will be removed when the sole is drawn down upon the last during the pulling-over and lasting operations.

Although the invention has been set forth as embodied in a particular mold designed to produce a particular sole, it should be understood that the invention is not limited in the scope of its application to the particular mold which has been shown and described.

Having thus described my invention, what I claim as new and desire to secure by Letters Patent of the United States is:

1. A mold for use in the manufacture of a rubber sole which has a sewing rib and an adjacent feather, said mold consisting entirely of two one-piece sections having contacting faces located in a common plane, one section being shaped to form the tread face and edge of the sole and the other section having a groove to form the rib and a surface to form the feather, the feather-forming surface in the forepart of the mold lying in the plane of the contacting surfaces of the sections and in the heel portion of the mold being inclined to said plane.

2. A mold for use in the manufacture of a rubber sole which has a sewing rib and an adjacent feather, said mold consisting entirely of two one-piece sections having contacting faces located in a common plane, one section being shaped to form the tread face and edge of the sole and the other section having a groove to form the rib and a surface to form the feather, the feather-forming surface in the forepart of the mold lying in the plane of the contacting surfaces of the sections and in the heel portion of the mold being inclined from said plane toward the rib-forming groove.

3. A mold for use in the manufacture of a rubber sole which has a sewing rib and an adjacent feather, said mold comprising a rib-forming section and a tread-forming section having contacting faces located in a common plane, the bottom of the groove in the forepart of the rib-forming section being located a less distance from said common plane than is the bottom of the groove in the rear part of the same section.

4. A mold for use in manufacturing a

rubber sole which has a sewing rib and an adjacent feather, said mold comprising two sections one of which has a groove adapted to form the rib and the other of which has 5 a cavity adapted to form the tread face and edge of the sole, the level of the bottom of the groove in the groove-forming section being different at different parts of the last-named section.

10 5. A mold for use in manufacturing a rubber sole which has a sewing rib and an adjacent feather, said mold comprising two sections one of which has a groove adapted to form the rib and the other of which has 15 a cavity adapted to form the tread face and edge of the sole, the level of the bottom of the groove in the forepart of the groove-forming section being different from the level of the bottom of the groove in the rear 20 part of the same section.

6. A mold for use in the manufacture of a rubber sole which has on its upper part a sewing rib, said mold comprising a section having a groove to form the rib and a surface 25 to form that portion of the upper face of the sole which lies between the runs of the rib, and a section having a cavity adapted to form the tread face and edge of the sole,

said sections having contacting faces located in a common plane, the distance from said 30 common plane of the surface adapted to form that portion of the upper face of the sole which lies between the runs of the rib being greater at the heel portion of the mold than at the toe portion. 35

7. A mold for use in the manufacture of a rubber sole which has a sewing rib and an adjacent feather, the feather being at right angles to the rib around the forepart of the sole and inclined downwardly around the 40 rear part of the sole comprising a rib-forming section and a tread-forming section shaped to hold the sole blank, during the molding and vulcanizing operations, bent in the locality of the heel breast line of the sole 45 blank, the sections having contacting faces located in a common plane and the bottom of the groove in the forepart of the rib-forming section being located at a less distance from said common plane than is the 50 bottom of the groove in the rear part of the same section.

In testimony whereof I have signed my name to this specification.

RALPH F. KNIGHT.
